UNITED STATES PATENT OFFICE.

JAMES ROBERT TINNEY, OF PHOENIX, ARIZONA.

PUMP.

1,398,450.

Specification of Letters Patent. Patented Nov. 29, 1921.

Application filed June 24, 1920. Serial No. 391,419.

To all whom it may concern:

Be it known that I, JAMES ROBERT TINNEY, a citizen of the United States, and resident of Phoenix, in the county of Maricopa and State of Arizona, have invented certain new and useful Improvements in Pumps, of which the following is a specification.

The present invention relates to pumps and more particularly to rotary pumps especially adapted for irrigation purposes.

The object of the invention is to provide a pump of this character in which the elements are so constructed, arranged and combined that the pump may be securely though detachably suspended in the well and will deliver from the well a volume of fluid limited only by the cross section of the well casing, the fluid delivered being constrained to substantially rectilinear upflow, all surging and whirling being eliminated, thereby to attain the highest efficiency with respect not only to the maximum output with minimum construction of power but also to all other respects.

Another object is to provide a pump of this character of simple and durable construction, reliable in operation and easy and inexpensive to manufacture.

Other objects and advantages will be hereinafter more fully described and particularly pointed out in the appended claims, reference being had to the accompanying drawings forming part of this specification in which:

Figure 1 is a side elevational view of one form of my invention, a portion of the well casing being shown in section for the sake of illustration,

Fig. 2 is a view in transverse vertical section,

Fig. 3 is a fragmentary view in vertical section showing one form of shell securing means in conjunction with an auxiliary shaft bearing,

Fig. 4 is a fragmentary view similar to Fig. 3 but on a plane at right angles thereto,

Fig. 5 is a plan of the preferred form of propeller,

Fig. 6 is a transverse horizontal section through the upper part of the shell showing the radial vanes,

Fig. 7 is a fragmentary detail view of the preferred form of means for preventing return flow of fluid between the shell and well casing.

Fig. 8 is a plan of the form shown in Fig. 7;

Fig. 9 is an elevational view, partly in section, of a modified form of my invention;

Fig. 10 is a transverse vertical section of the shell of this modified form;

Fig. 11 is a transverse horizontal section of the upper portion of the shell; and

Fig. 12 is a detail view in side elevation of a modified form of fluid impeller.

The pump comprises a shell 11, preferably of cylindrical form and of such size as to be a snug working fit in the well casing 10. The upper or delivery end of the shell is provided with means to prevent down flow of the fluid between the well casing and the shell which may consist of a rubber gasket-like structure 12 but which preferably embodies a plurality of inverted frusto-conical sections 13 as shown in Figs. 7 and 8. These sections have their lower ends riveted to the shell. The adjacent ends of the sections overlap and when the pump is not delivering fluid the sections are slightly spaced from the well casing. When the pump is delivering fluid, the pressure of the fluid expands the sections against the well casing and effects a seal between the shell and the casing. The pressure acts upon the rubber gasket-like structure in a similar manner.

The shell 11 is supported in the well casing by a hanger which may be in the form of a rod 14, eccentrically disposed and having its lower end riveted to the shell 11, as at 15, and its upper end crooked as at 16 to engage the upper end of the well casing. The crooked end 16 is provided with a swiveled joint 17 to permit the outer portion to be turning as indicated in dotted lines in Figs. 1 and 2. The eccentricity of the rod may be thus utilized to tighten the shell 11 in place in the casing. In the preferred form of supporting means the lower end of the supporting rod is threaded as shown at 18 in Fig. 3, the threaded portion of the rod being engaged in the nut 19 carried by the shell 11. A swivel 20 is carried by the lower end of the rod, the eye 21 of which is pivotally secured to the bell crank lever 22 pivotally mounted to the casing. A dog 23 is pivotally mounted on the bell crank lever and projects through a suitable opening in the shell 11 to engage the wall of the well casing.

A shaft 24 is arranged to extend centrally of the well casing and the shell down-

wardly from the surface of the ground through the shell and is supported in the form of my invention shown in Figs. 1 and 2 by a spindle bearing. The spindle bearing 5 comprises a housing 25 carried by bracket arms 26 secured to the lower end of the shell. The housing 25 contains the Babbitt metal or other bearing metal which directly engages the lower end of the shaft.

10 The shaft 24 drives the rotary element or fluid propeller 27 of the pump, the motion being communicated to the shaft by suitable gearing such as a belt and pulley 28 and 29 respectively, driven from any suitable form 15 of power plant (not shown).

The rotary element 27 of the pump in all embodiments of the invention is disposed well down within the casing and in the form shown in Figs. 1 and 2 is disposed adjacent 20 the lower end thereof. In this form the rotary element comprises a disk slotted as at 30 from the periphery of the disk inwardly for a substantial distance on a diameter as seen in Fig. 5 and then bent to form a propeller as seen in Fig. 2. The disk is welded 25 to the shaft as shown at 31 in Fig. 2.

A plurality of radial vanes 32 are arranged in the shell and extend from the top of the propeller to the upper end of the casing. The lower ends of the vanes are just 30 clear of the propeller that is while they are disposed so as not to lie in the path of the propeller at any time they do lie immediately above the same. The inner ends of 35 the vanes are preferably carried by a sleeve 33 which embraces the shaft 24 which is however free to rotate relative thereto. The longitudinal edges of the vanes are bent to 40 form curve flanges 34 secured respectively to the sleeve and the shell in any suitable manner.

As shown in Figs. 3 and 4 the propeller 24 may be disposed approximately centrally of the shell, the length of the vanes being correspondingly shortened. The lower end of 45 the propeller carries a bearing collar 35 which with the tub 36 formed on the spider arms 37 constitutes an auxiliary bearing. This auxiliary bearing preferably supplements but may take the place of the spindle 50 bearing. The outer ends of the spider arms are elongated and attached in any conventional manner to the interior wall of the shell.

55 The shaft 24 is preferably constructed in two sections, the upper section being provided with a squared axial socket 38 to receive the squared end 39 of the lower section. The end 39 is provided with a slot 40 extending longitudinally of the shaft. A cross pin 41 is carried by the end walls of the socket 38 and extends through the slot. The sections are thus constrained to each partake 60 of the rotary movement of the other but 65 may be moved longitudinally of each other

for a distance limited by the length of the slot and the diameter of the cross pin. This connection provides for the expansion and contraction of the shaft and is also used as a jar in pulling the pump.

70 In the form of my invention shown in Figs. 9 to 12, inclusive, the shell 11 is positioned as usual in the well casing 10. In the means for sustaining the shell in this form of my invention, the rod 14 depends vertically within the casing and is carried by the top of the well casing, an apertured bearing plate 43 serving as a seat for the adjusting nut 44 which is carried by the upper end of the rod. The lower end of the rod 14 extends through a smooth bored bracket 45 secured to the shell 11 and the lower extremity of the rod beneath the smooth bored bracket has a swivel connection 46 to the bell crank 47 which bell crank carries a pivoted dog 48 for engaging the well casing.

75 In this embodiment of my invention the length of the shell is equal to its diameter, it being found that these proportions are adequate to meet the exigencies of a large 80 number of uses. The radial vanes 32 which are carried by the shell as in the other embodiment of the invention are somewhat shorter but are of sufficient extent to effect 85 their purpose.

90 As shown in detail in Fig. 12, the rotary element of the pump in this form of the invention includes a hub 49 having a spiral impeller 50 integrally formed therewith. The hub 49 is keyed, as at 51, to the drive shaft 100 24. The peripheral edge of the impeller 50 is beveled upwardly as indicated at 51, whereby the friction surface between the impeller and the shell is minimized to eliminate the deleterious effects of banding or 105 the like.

95 In operation the pump having been suspended in the well and secured in place and motion having been imparted to the propeller, the fluid in the well will be lifted by 110 the propeller. The propeller however in acting upon the fluid not only forces the same upwardly but also tends to impart a whirling motion to the same which produces surging and the like in the shell. The latter tends to reduce the output of fluid by 115 decreasing the efficiency of the pump. These tendencies of the propeller are overcome in the present invention for the fluid delivered from the propeller is received in the spaces 120 between the vanes which arrest such motion and constrain the fluid to substantially rectilinear upward motion therein and thereafter in the well casing and in fact throughout the entire conduit defined by these members and any similar member that may be connected thereto for conveying the fluid to the desired point.

125 The position of the shell in the well casing may be adjusted to suit the conditions 130

and in any position to which the shell is adjusted the packing means carried by the upper end thereof is operative to effect the desired seal between the shell and the upper 5 end of the well casing.

I claim:—

1. In a device of the character described, in combination with a well casing, of a shell arranged in said well casing, means for 10 supporting said shell including a hanger rod adapted to be turned to secure the shell in the casing, a shaft in said well casing extending through said shell, a bearing for said shaft carried by said shell and a propeller mounted upon said shaft within the 15 shell.

2. In a device of the character described including a shell, and a rotary element for impelling the fluid operatively mounted in 20 said shell, said rotary element having its peripheral edge beveled upwardly to minimize the friction surface as between the rotary element and the shell.

3. In a device of the character described, in combination with a well casing, a pump 25 arranged in said well casing including a shell suspended therein, and means for sustaining said shell consisting of a rod, a bearing plate and adjusting nut for adjustably 30 securing the upper end of said rod to the cap of the well casing, a smooth bored

bracket carried by the shell and receiving the lower end of said rod, and a dog operated by the lower extremity of said rod, and a rotary element arranged in said shell 35 for impelling the fluid.

4. In a device of the character described, in combination with a well casing, a pump arranged in said well casing including a shell suspended therein and means for suspending said shell consisting of a rod, a bearing plate and adjusting nut for adjustably 40 securing the upper end of said rod to the cap of the well casing, a smooth bored bracket carried by the shell and receiving 45 the lower end of said rod, a dog operated by the lower extremity of said rod, a rotary element arranged in said shell for impelling the fluid, and vanes extending for a substantial distance longitudinally of the shell to 50 constrain the fluid delivered from the pump to rectilinear motion, all as and for the purposes set forth.

5. In a device of the character described, a pump including a shell, a drive shaft extending through said shell and a rotary element having a hub keyed to said drive shaft and a spiral blade having its peripheral edge beveled upwardly, all as and for the 55 purposes set forth.

JAMES ROBERT TINNEY.
